UNITED STATES PATENT OFFICE.

BENJAMIN WOLHAUPTER, OF NEW YORK, N. Y., ASSIGNOR TO THE RAIL JOINT COMPANY, OF NEW YORK, N. Y., A CORPORATION OF NEW YORK.

REINFORCED ANGLE-BAR FOR RAIL-JOINTS.

No. 878,589.

Specification of Letters Patent.

Patented Feb. 11, 1908.

Application filed January 19, 1897. Serial No. 353,014.

To all whom it may concern:

Be it known that I, BENJAMIN WOLHAUPTER, a citizen of the United States, residing at New York city, in the county of New York and State of New York, have invented a certain new and useful Improvement in Reinforced Angle-Bars for Rail-Joints, of which the following is a specification.

This invention relates to the subject of rail joints, and more particularly to rail joint angle bars of the type commonly termed splice bars.

The main and primary object of the invention is to provide a simple and practical design of reinforced angle bar capable of being applied with the same facility and readiness as the conventional forms of splice bars or fish plates, while at the same time being reinforced in a novel and efficient manner so as to provide a bar of maximum strength with a minimum amount of material.

A special object of the invention is to provide what may be characterized as a double reinforced angle bar which carries the reinforcement of the lower chord of the girder over the surface of the ties, whereby the load is carried clear of the corners of the ties, and distributed over the surface of the latter.

As a general object, the invention has in view the provision of a simple design of reinforced angle bar possessing exceptional strength and a powerful stiffening and bracing effect without sacrificing any of the necessary qualities of proper weight, rigidity, and sufficient resiliency.

With these and many other objects in view, which will readily appear to those familiar with the art as the nature of the invention is better understood, the same consists in the novel construction, combination, and arrangement of parts hereinafter more fully described, illustrated, and claimed.

The essential feature of the invention involved in the novel reinforcement of the angle bar is necessarily susceptible to embodiment in various designs of bars and in various types of rail joint plates without departing from the scope of the invention, but for illustrative purposes certain preferred embodiments of the latter are shown in the accompanying drawings, in which:

Figure 1 is a perspective view of a rail joint embodying in its construction the improved double reinforced angle bars. Fig. 2 is a side elevation of the joint shown in Fig.

1. Fig. 3 is a cross sectional view on the line 3—3 of Fig. 2. Fig. 4 is a similar view on the line 4—4 of Fig. 2. Fig. 5 is a side elevation of a rail joint having a modified design of angle bar constructed in accordance with the present invention. Fig. 6 is a cross sectional view on the line 6—6 of Fig. 5. Fig. 7 is a similar view on the line 7—7 of Fig. 5.

Like references designate corresponding parts in the several figures of the drawings.

In the embodiment of the invention shown in the group of Figs. 1 to 4 inclusive of the drawings, the rail joint comprises, in combination with the adjacent service or running rails 1 and 2, the oppositely arranged side angle bars 3, and the usual series of joint bolts 4 passing through the aligned bolt holes in the bars and the webs of the rails. Hence, the present invention involves no change in the general form and manner of setting up the ordinary types of rail joints employing angle bars or splice bars, but has special reference to the design and reinforcement of the individual angle bars.

Referring particularly to the design and construction of each angle bar 3, the same essentially consists of a main, straight, splice bar portion 5 formed at its upper edge with the usual head or head flange 6, and at its lower edge with the inclined outturned foot flange 7 overlying the inclined top surface of the base flange of the rails, and usually formed in the outer edges thereof, contiguous to the ends of the bar with the spiking notches 8 overlying the usual track ties T which are located respectively at opposite sides of the vertical plane of the joint between the meeting ends of the rails 1 and 2.

In addition to the usual elements above referred to, the present invention contemplates forming each angle bar 3 with a lower girder chord 9 in the form of a flange deflected downwardly from the outer edge of the foot flange 7 centrally between the ends of the latter so as to lie in a downwardly projecting position between the two ties T. Hence, the lower girder chord 9 constitutes a centrally arranged pendent stiffening girder extending below the rail bases and lying in the vertical transverse plane of the joint between the meeting ends of the rails. In the form of the invention shown in Figs. 1 to 4 inclusive of the drawings, the centrally arranged pendent stiffening girder between

the ties is set at an angle to a vertical plane and projects inwardly toward the longitudinal center line of the rails. But, irrespective of the angle or disposition of the 5 pendent stiffening girder 9, a feature of the invention resides in continuing from the opposite edges of such girder the horizontal girder flange extensions 10 which project in substantially horizontal planes outwardly 10 from the edge of the foot flange 7 and extend over the surface of the ties, as may be plainly seen from Figs. 1 and 2 of the drawings. As indicated, the horizontal girder flange extensions 10 merge into the girder or girder 15 chord 9, and to provide for an extra reinforcement of the angle bar, the same is formed along the edge of its pendent girder 9 and the projecting girder flanges 10 with a reinforcing rib. The portion of the reinforcing rib which extends along the bottom edge 20 of the stiffening girder 9 is designated by the reference number 11, while the portions thereof which reinforce the edges of the flanges 10 are designated by the reference 25 number 12. The rib portions or sections 11 and 12 are preferably continuations of an integral continuous ribbed formation, and merge into each other through the corner rib sections 13 which twist from the vertical 30 plane of the rib sections 12 to the horizontal plane of the rib section 11. In this connection, it will be observed that the said rib section 11 preferably projects outwardly from the lower bottom edge of the pendent 35 girder 9, while the rib sections 12 project in an upward direction from the outer edge of the girder flange extensions 10.

The construction described provides a double reinforcement for each angle bar, and 40 by reason of the fact that the girder flanges 10, and their reinforcing or stiffening ribs 12, extend well over the ties, the load is carried clear of what may be termed the inside corners of the ties with reference to the joint, 45 with the consequence of distributing the load over the surfaces of the ties instead of leaving weak places or points in the bars over the said inside corners of the ties as in other designs of sheared angle bars.

50 A modification which may be resorted to in the design of the double reinforced angle bar is suggested by the construction shown in Figs. 5, 6, and 7 of the drawings, and referring thereto, it will be observed that the 55 same distinctive feature is preserved of carrying the girder reinforcement over the surface of the ties and beyond the inside corners thereof. However, in the modified structure, the centrally arranged pendent 60 stiffening girder or girder chord 9 is illustrated as lying in a substantially perpendicular plane and provided with a plain non-reinforced bottom edge, but the side edges of the side girder or girder chord 9^a are shown 65 as having formed thereon the outstanding re-

inforcing ribs 11^a which are continued into the upper horizontal rib sections 12^a formed integrally with the outer edges of the girder flange extensions 10, and together with the latter extend well over the surface of the ties 70 to distribute the load thereover in the manner already explained.

The same mechanical feature of continuing the double girder reinforcement from the pendent girder member to points over the 75 surface of the ties beyond the inside corners of the latter, may obviously be embodied in various designs of angle or splice bars, and the reinforcement itself shaped and arranged in divers ways without departing from the 80 invention, so it will be understood that various changes in the form, proportion, and minor details of invention may be resorted to without departing from the spirit or sacrificing any of the advantages of the invention. 85

In the manufacture of angle bars embodying the present invention, the same may be made either by the ordinary molding operation for cast bars, or by the rolling, shearing, 90 and setting up process usually employed in the making of rolled rail joint plates or angle bars. In forming the bars by the latter process, the girder elements 9 and 10 are preferably first rolled into substantially a 95 common plane, and then one or both of said elements bent into the final position. For instance, the bar may be rolled so that the girder elements 9 and 10, in their first position, will occupy the plane of the element 10 as shown in Fig. 3, and then the pendent girder 9 bent down to its proper relative plane. Or, this operation can be reversed, 100 viz: by rolling the bar so that both girder elements, in their first position, will occupy 105 the plane of the pendent girder element as shown for instance in Fig. 7, and then the girder elements or extensions 10 bent up into their final relative plane shown in Fig. 6. Again, in the rolling operation, the girder 110 elements may be first rolled to a position intermediate the final positions of both the elements 9 and 10, and then the latter bent or set-up into said final positions. However, 115 these or other methods of forming the improved double reinforced bars may be resorted to without affecting the mechanical features thereof constituting the subject matter of this application.

I claim:

1. An angle bar for rail joints provided with a stiffening girder and a continuous reinforcement for said girder arranged to extend over the tops of the ties to carry the load clear of the corners of the ties.

2. An angle bar for rail joints provided with a pendent stiffening girder and a continuous reinforcement for said girder arranged to extend beyond the latter and over the tops of the ties.

3. An angle bar for rail joints provided with a pendent stiffening girder, girder extensions arranged to extend over the ties, and a reinforcement for the girder and girder 5 extensions.

4. An angle bar for rail joints provided with a pendent stiffening girder, horizontal girder extensions arranged to overlie the ties, and a reinforcement for the girder and girder 10 extensions.

5. An angle bar for rail joints provided with a stiffening girder, horizontal girder extensions merged with said girder and arranged to overlie the ties, and a reinforcement 15 for the girder and girder extensions.

6. An angle bar for rail joints provided with a stiffening girder and horizontal girder flange-extensions merged with said girder and arranged to extend over the surfaces of 20 opposite track ties, and a reinforcement extending along the girder and girder flange-extensions.

7. An angle bar for rail joints provided with a stiffening girder, horizontal girder flange-extensions projecting outwardly from 25 the foot flange of the angle bar and arranged to overlie the surfaces of the opposite ties, said girder flange-extensions being integral

with the girder, and a reinforcement for both said girder and the girder flange-extensions. 30

8. An angle bar for rail joints provided with a pendent stiffening girder adapted to lie between the ties, horizontal flange-extensions projected from the foot flange and merged with opposite end portions of the 35 pendent girder, and reinforcing ribs formed integrally with and extending along the edges of the pendent girder and the girder flange-extensions.

9. An angle bar for rail joints provided 40 with an intermediate pendent stiffening girder, horizontal girder flange-extensions merged with opposite end portions of the girder, and projecting from the foot flange of the bar, said girder flange-extensions being ar- 45 ranged to project beyond the inner corners of the ties and overlying the surfaces of the latter, and a continuous reinforce rib projected from and following the edges of the pendent girder and girder flange-extensions. 50

In testimony whereof I hereunto affix my signature in the presence of two witnesses.

BENJAMIN WOLHAUPTER.
